Int. Cl. D30—99

U.S. Cl. D30—99

FIG. 1 is a side elevation view of a dog supported disposable waste bag for droppings, embodying my new design;

FIG. 2 is a rear elevational view;

FIG. 3 is a perspective view;

FIG. 4 is a front elevational view; and

FIG. 5 is a top plan view.

The dog which is fragmentarily shown in broken lines in FIGS. 1 and 2 is included for illustrative purposes only.

This is a continuation-in-part of design application Ser. No. 238,719, filed Mar. 27, 1972, now Pat. No. 229,321.

I claim:

The ornamental design for a dog supported disposable waste bag for droppings, substantially as shown and described.
